US0D1018481S

(12) **United States Design Patent** (10) **Patent No.:** **US D1,018,481 S**
(45) **Date of Patent:** **** Mar. 19, 2024**

(54) **MASSAGER CONTROLLER**

(71) Applicant: **Shenzhen Jiantuo Electronics Co., LTD**, Shenzhen (CN)

(72) Inventor: **Jinliang Zou**, Shenzhen (CN)

(73) Assignee: **Shenzhen Jiantuo Electronics Co., LTD**, Shenzhen (CN)

(**) Term: **15 Years**

(21) Appl. No.: **29/918,403**

(22) Filed: **Nov. 28, 2023**

(51) **LOC (14) Cl.** **14-03**

(52) **U.S. Cl.**

USPC **D13/168**; D24/200

Primary Examiner — Selina Sikder

(57) **CLAIM**

The ornamental design for a massager controller, as shown and described.

DESCRIPTION

FIG. 1 is a first perspective view of a massager controller showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the massager controller that form no part of the claimed design.

1 Claim, 8 Drawing Sheets
